TRIGGER MECHANISM

John C. Garand, Springfield, Mass.

Application July 29, 1942, Serial No. 452,769

14 Claims. (Cl. 42—3)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to a trigger mechanism for an automatic firearm and particularly to such a firearm which is to be fired only semi-automatically.

An object of this invention is to produce an improved trigger mechanism for firearm. A particular object of this invention is to produce a semi-automatic firing trigger mechanism which will maintain its semi-automatic characteristics even though a faulty cartridge may be fired which does not provide sufficient energy to drive the bolt mechanism through its complete cycle. A further object of this invention is to provide a semi-automatic firing trigger mechanism having an improved, positive acting safety.

The specific nature of the invention as well as other objects and advantages thereof will clearly appear from a description of a preferred embodiment as shown in the accompanying drawings in which:

Figure 1 is a longitudinal sectional view of the trigger mechanism shown in the cocked position.

Figure 2 is a longitudinal section view of the trigger mechanism shown with the trigger released.

Figure 3 is a longitudinal sectional view showing the trigger in the released position and the operating rod at the end of the bolt recoil movement.

Figure 4 is a right end elevational view partly in section of Figure 3.

Figure 5 is a perspective view of the sear.

Figure 6 is a perspective view of the detent. The trigger mechanism to be described is particularly adaptable for use in an automatic firearm of the general type described in detail in my copending application, Serial No. 426,036, filed January 8, 1942, but it should be understood that this improved trigger mechanism is equally adaptable for use in any automatic firearm wherein a reciprocating bolt member is utilized.

As shown in Figure 1 in assembled relation, the improved trigger mechanism comprises a trigger frame member 1. The forward end of the frame member 1 comprises two side walls 1a and 1b which, with a forward end wall (not shown) define a chamber 1d in which the magazine (not shown) and various trigger components are mounted. The rear end of the trigger frame is provided with a depending trigger guard portion

1e and at the extreme rear end of the frame a countersunk hole 1f is provided. The rear portion of the trigger mechanism may be secured to the receiver and the stock by means of a bolt passing through the hole 1f and threaded into the receiver and/or the stock (not shown).

When the trigger frame is assembled to a firearm, the rear portion of the frame should underlie the path of the reciprocating bolt member utilized in the particular firearm, or in the path of a member secured to such bolt which reciprocates therewith, such for example, as an operating rod 2 which is shown diagrammatically in the drawings. This rod 2 is secured to the bolt in any desired manner. Such member should be provided with a front-facing surface 2a suitable for engagement by a sear.

The sear 3 is pivotally mounted in the top rear portion of the frame chamber 1d on a transverse pin 10 which is supported by the side walls 1a and 1b of the trigger frame. The pivoted end of the sear 3 is bifurcated and an opening 3a in the sear is thereby provided. A magazine latch 5 is also mounted on the pin 10, the latch having a rearwardly extending projection 5a. The projection 5a extends into the opening 3a provided in the sear and a hole 5b in such extension permits the magazine latch to be pivotally mounted on the pin 10. The sear 3 extends rearwardly from its pivoted mounting and in its central portion is provided with a sear shoulder 3b which engages the latching surface 2a on the operating rod to hold the operating rod in the cocked position of the firearm.

The rear portion of the sear 3 is provided with a pair of depending ears 3c. Between such ears the top portion of a trigger 4 is pivotally mounted as by the rivet or pin 14 which extends through the depending ears 3c. A trigger spring 6 has one end inserted in a spring chamber 4a provided in the trigger 4 and its other end engages a spring seat 3d provided in the rear face of the sear 3 and above the rivet 14. The spring 6 thereby exerts a force tending to pivotally separate the trigger 4 and the sear 3. Such separation is prevented by the front surface of the trigger 4 engaging a transverse pin 8 mounted in the trigger frame 1 underneath the trigger 4. The trigger 4 extends through the trigger notch 1h in the frame 1 into the space defined by the trigger guard portion 1e of the frame 1. The portion of the trigger extending into this space is of conventional shape. The rear surface of the trigger 4 is provided with stepped surfaces 4b and 4c, respectively the upper and lower of such

steps. A fulcrum or detent member 7 is provided to engage such step surfaces to permit the operation of the trigger mechanism. The detent member 7 is of approximate T-shape having a bifurcated stem 7a inclined with respect to the head 7b. The bifurcated stem 7a surrounds the trigger 4 and is pivotally mounted in the trigger frame 1 on transverse pin 8. A U-shaped torsion spring 9 is wrapped around the pin 8 and exerts a force between the trigger frame 1 and the detent 7, biasing the detent in a clockwise direction as viewed in Fig. 1. The forward edge 7c of the head 7b is thereby biased into engagement with the notch of the top trigger step surface 4b. In this position the head 7b of the detent extends upwardly at an angle of about 30° and projects into the path of rearward movement of the operating rod 2. Such movement of course occurs immediately following the discharge of a cartridge. The bottom rear surface 2b of the operating rod 2 is rounded as at 2b so that detent 7 may be struck by such surface without injury to the detent.

The engagement of the edge 7c of the detent 7 in the notch of the step surface 4b of the trigger 4 provides a fulcrum point permitting the operation of the trigger. Thus on pulling the trigger 4, it pivots about the edge 7c lowering the extreme forward end of the trigger and thereby pivoting the sear 3 counterclockwise about the pin 10. This leverage arrangement provides the primary trigger pressure. After slight pivotal movement of the trigger under the trigger pull applied, a projection 4d, formed by the base of step 4c, contacts surface 7d at the base of the bifurcated portion of the detent 7. This contact point now acts as the fulcrum for the trigger and supplies a secondary trigger pressure of roughly twice as great due to shift in position of the trigger fulcrum. This change of fulcrum does not affect the path of movement of the sear 3 and it continues to pivot counterclockwise about the pin 10. Thus the sear notch 3b is pulled out of engagement with the latching surface 2a on the operating rod 2, permitting the operating rod to drive forward under the influence of the operating spring to fire the firearm. Upon discharge of a cartridge, the operating rod 2 being secured to the bolt (not shown) is driven rapidly to the rear. The bottom rear surface 2b of the rod engages the top of the head 7b of the detent 7 and as the rear movement of the detent 7 is continued, the detent 7 is forcibly pivoted in a counterclockwise direction. This pivoting removes the forward edge 7c of the detent from engagement with the notch of the step 4b in the trigger and surface 7d of the detent from engagement with projection 4d. If the trigger has been released by this time, the sear assumes its cocked position under the influence of the spring 6 and the next cartridge may be fired by pulling the trigger. If however there is still a pulling force exerted on the trigger at this time, the removal of the detent from the rear of the trigger destroys the fulcrum on which the trigger was pivoted and the fulcrum for the trigger lever system then becomes the pin 14. Hence the sear 3 pivots back into its cocked position under the influence of the spring 6 and the trigger pull and engages the surface 2a of the operating rod as that member drives forward, arresting it in the cocked position. The forward movement of the operating rod 2 of course frees the detent 7 for clockwise pivotal movement under the influence of spring 9. If the trigger is still pulled the end 7c

of the detent strikes the vertical surface of trigger step 4c but this contact does not provide a fulcrum for the trigger which would permit the operation of the trigger. Hence the trigger must be released whereupon the detent edge 7c rides out of step 4c and into wedging engagement in the notch of step 4b ready for another firing cycle. Of course if the trigger has been released when detent 7 is released from the operating rod, then the detent edge 7c immediately pivots into the notch of step 4b under the influence of spring 9. Under any conditions then it is necessary to release the trigger before a second cartridge is fired, thus assuring semi-automatic operation of the firearm.

The safety mechanism for this improved trigger construction utilizes a spring 11 common to the magazine latch 5. A vertical spring chamber 1j is provided in the trigger frame 1 in the portion underlying the rearward magazine extension 5a. This chamber 1j extends clear through the frame 1. A spring 11 is mounted in this chamber, the top end of the spring engaging the extension 5a of the magazine latch while the bottom end of the spring is secured in a spring seat detent 12 which is inserted in the chamber 1j in such a manner as to permit vertical movement of the detent 12 with respect to the frame 1. The detent 12 is held up in the chamber 1j by the safety slide 13. This slide 13 is mounted in oppositely disposed horizontal grooves 1k provided in the bottom of the side walls 1a and 1b of the trigger frame. The top surface of the safety slide 13 supports the detent 12 irrespective of the position of the safety slide 13. This top surface of the safety slide 13 is given a saw-tooth configuration as indicated at 13a. The bottom surface of the detent 12 is correspondingly shaped. Thus by engagement of such surfaces the safety slide 13 is resiliently secured in either a forward or a rearward position by the detent 12. Attached to the central portion of the safety guide and projecting vertically upward between the frame side walls 1a and 1b is a locking extension 13b. In a rearward position of the safety 13, this extension is brought directly under two small depending projections 3e provided respectively on the bottom of the ears 3c of the sear 3. With the safety slide in this rearward position, pivotal movement of the sear in a direction to release the sear notch 3b from engagement with the operating rod 2 is prevented by the projections 3e striking the safety lock 13b. In the forward position of the safety slide 13, the safety lock 13b is moved out of the path of the sear projection 3e and hence the trigger mechanism is rendered operative. An integrally formed arm 13c of the safety slide projects below the slide portion and terminates in a horizontal button 13d which reciprocates through a hole 1m in the front end of the trigger guard 1e. The safety may thus be readily manipulated by the operator of the firearm since it may be grasped by his trigger finger.

A special feature of the foregoing construction lies in the fact that it is not possible to obtain automatic fire of the weapon even when the operating rod does not travel the full distance rearwardly due to discharge of a defective cartridge. The position of the detent 7 with respect to the operating rod 2 can be so designed that the detent 7 is pivoted out of engagement with the notch of the step surface 4b of the trigger when the operating rod has reached such a rearward position as to insure that a new cartridge will be

picked up by the bolt on its forward movement. Hence each time that there is sufficient recoil movement of the operating rod 2 to load a new cartridge into the chamber of the firearm the detent 7 will be pivoted out of engagement with both the notch 4b and the projection 4d of the trigger and hence the sear 3 will be released to return to its cocked position under the bias of spring 6. Thus any recoil movement of the bolt and operating rod sufficient to produce the loading of a cartridge will also return the sear to its cocked position, preventing the uncontrolled firing of such cartridge.

I claim:

1. A trigger mechanism for a firearm comprising a trigger frame, a sear pivotally mounted to the trigger frame, a trigger pivotally secured to the sear, compressed first resilient means mounted between the trigger and sear, stop means on said trigger frame for limiting the pivotal movement of said trigger under the bias of said first resilient means, a fulcrum member pivotally mounted on the trigger frame, said fulcrum member having one portion arranged to engage a first fixed area on the rear of said trigger, a second resilient means biasing said fulcrum member into engagement with said trigger thereby providing a first fulcrum about which the trigger may be initially pulled to pivot said sear about its mounting and a second portion on said fulcrum member engageable by a second fixed area on the rear of said trigger after limited pulling movement of said trigger thereby providing a second fulcrum for further pivotal movement of said trigger.

2. A trigger mechanism for a firearm comprising a trigger frame, a sear pivotally mounted on the trigger frame, a trigger pivotally secured at its forward end to the rear end of the sear, a compressed spring mounted between said trigger and sear, a transverse pin in the trigger frame limiting the movement of the trigger under such spring bias, a notch on rear of said trigger, a detent pivotally mounted on said pin and resiliently biased into engagement with said notch on the rear of the trigger thereby providing a fulcrum about which the trigger may be pulled to pivot said sear about its mounting.

3. A trigger mechanism for a firearm comprising a trigger frame, a sear pivotally mounted to the trigger frame, a trigger pivotally secured to the sear, compressed first resilient means mounted between the trigger and sear, stop means on said trigger frame for limiting the pivotal movement of said trigger under the bias of said first resilient means, a detent having a bifurcated portion surrounding said trigger, said detent being pivotally mounted to the trigger frame at the end of its bifurcated portion, a second resilient means biasing said detent into engagement with the rear surface of the trigger to provide a fulcrum for primary trigger pull, a projection on said trigger lying within the bifurcated portion of the detent, said projection arranged to engage said detent after slight movement of the trigger to thereby provide a fulcrum for secondary trigger pull.

4. A trigger mechanism for a firearm comprising a trigger frame, a sear pivotally mounted on the trigger frame, a trigger pivotally secured at its forward end to the rear end of the sear, a compressed spring mounted between said trigger and sear, a transverse pin in the trigger frame limiting the movement of the trigger under such spring bias, a detent having a bifurcated

portion surrounding said trigger, said detent being pivotally mounted on said transverse pin at the end of its bifurcated portion, resilient means biasing said detent into engagement with the rear surface of the trigger to provide a fulcrum for primary trigger pull, a projection on said trigger lying within the bifurcated portion of the detent, said projection arranged to engage said detent after slight movement of the trigger to thereby provide a fulcrum for secondary trigger pull.

5. In an automatic firearm, in combination, a recoiling member reciprocable in a straight line path, a trigger frame, a sear pivotally mounted to the trigger frame and arranged to engage said recoiling member near the forward end of its movement, a trigger pivotally secured to the sear, compressed first resilient means mounted between the trigger and sear, operating to bias said sear into a cocked position relative to said recoiling member, stop means on said trigger frame for limiting the pivotal movement of said trigger under the bias of said first resilient means, a notch on the rear of said trigger, a T-shaped detent having its base pivotally secured to the trigger frame, a second resilient means pivotally biasing the forward end of the head of said detent into engagement with said notch on the rear of said trigger thereby providing a fulcrum about which the trigger may be pulled to pivot the sear, the rear end of the head of said detent projecting into the recoil path of the recoiling member and actuated thereby to remove said detent out of engagement with the trigger notch thereby permitting the sear to return to its cocked position under the bias of said first resilient means.

6. In an automatic firearm having a recoiling member, a trigger mechanism comprising a trigger frame, a sear pivotally mounted on the trigger frame, a trigger pivotally secured at its forward end to the rear end of the sear, a compressed spring mounted between said trigger and sear, a transverse pin in the trigger frame limiting the movement of the trigger under spring bias, a T-shaped detent having a bifurcated stem portion surrounding said trigger, said detent being pivotally mounted on said transverse pin at the end of its bifurcated portion, a notch on the rear of said trigger, resilient means pivotally biasing the forward end of the head of said detent into engagement with said notch on the rear of said trigger, thereby providing a fulcrum about which the trigger may be pulled to pivot the sear, the rear end of the head of said detent arranged to project into the recoil path of the recoiling member, said detent being pivoted out of engagement with the trigger by recoil movement of the recoiling member thereby permitting the sear to return to its cocked position under the bias of said compressed spring.

7. In an automatic firearm having a recoiling member, a trigger mechanism comprising a trigger frame, a sear pivotally mounted to the trigger frame, a trigger pivotally secured to the sear, compressed first resilient means mounted between the trigger and sear, stop means on said trigger frame for limiting the pivotal movement of said trigger under the bias of said first resilient means, a T-shaped detent having a bifurcated stem portion surrounding said trigger, said detent being pivotally secured to the trigger frame at the end of its bifurcated portion, a notch on the rear of said trigger, a second resilient means pivotally biasing the forward end of the head of said detent into engagement with said notch on the rear of said trigger thereby providing a fulcrum

about which the trigger may be initially pulled to pivot the sear, a projection on the rear of said trigger lying within the bifurcated portion of the detent, said projection engaging said detent by movement of the trigger to thereby provide a fulcrum for secondary trigger pull, the rear end of the head of said detent arranged to project into the recoil path of said recoiling member, said detent being pivoted entirely out of engagement with the trigger by recoil movement of the recoiling member thereby permitting the sear to return to its cocked position under the bias of said first resilient means.

8. In an automatic firearm, in combination, a recoiling member reciprocable in a straight line path, a trigger frame, a sear pivotally mounted on the trigger frame and arranged to engage said recoiling member near the forward end of its movement, a trigger pivotally secured to the sear, compressed first resilient means mounted between the trigger and sear and operating to bias said sear into a cocked position relative to said recoiling member, stop means on said trigger frame for limiting the pivotal movement of said trigger under the bias of said first resilient means, a T-shaped detent having its base pivotally secured to the trigger frame, a first notch on the rear of said trigger, a second resilient means pivotally biasing the forward end of the head of said detent into engagement with a said first notch on the rear of said trigger thereby providing a fulcrum about which the trigger may be pulled to pivot the sear, a second notch on the rear of the trigger adjacent the said first notch, the rear end of the head of said detent projecting into the recoil path of the recoiling member and actuated thereby to remove said detent out of engagement with the trigger thereby permitting the sear to return to its cocked position under the bias of said first resilient means, said second notch arranged to be engaged by the forward end of the head of said detent if the trigger remains pulled after the recoiling member returns to cocked position, thereby requiring release of the trigger pull to render the trigger operative.

9. In an automatic firearm having a recoiling member, a trigger mechanism comprising a trigger frame, a sear pivotally mounted on the trigger frame, a trigger pivotally secured at its forward end to the rear end of the sear, a compressed spring mounted between said trigger and sear, a transverse pin in the trigger frame limiting the movement of the trigger under such spring bias, a T-shaped detent having a bifurcated stem portion surrounding said trigger, said detent being pivotally mounted on said transverse pin at the end of its bifurcated portion, a first notch on the rear of said trigger, resilient means pivotally biasing the forward end of the head of said detent into engagement with said first notch on the rear of said trigger, thereby providing a fulcrum about which the trigger may be pulled to pivot the sear, a second notch on the rear of the trigger adjacent the said first notch, the rear end of the head of said detent arranged to project into the recoil path of said recoiling member, said detent being pivoted out of engagement with the trigger by recoil movement of the recoiling member thereby permitting the sear to return to its cocked position under the bias of said compressed spring, said second notch arranged to be engaged by the forward end of the head of said detent if the trigger remains pulled after the recoiling member returns to battery position, thereby requiring release of the trigger pull to render the trigger operative.

10. In an automatic firearm having a recoiling member, a trigger mechanism comprising a trigger frame, a sear pivotally mounted to the trigger frame, a trigger pivotally secured to the sear, compressed first resilient means mounted between the trigger and sear, stop means on said trigger frame for limiting the pivotal movement of said trigger under the bias of said first resilient means, a T-shaped detent having a bifurcated stem portion surrounding said trigger, said detent being pivotally secured to the trigger frame at the end of its bifurcated portion, a first notch on the rear of said trigger, a second resilient means pivotally biasing the forward end of the head of said detent into engagement with said first notch on the rear of said trigger thereby providing a fulcrum for secondary trigger pull, the rear end of the head of said detent arranged to project into the recoil path of the recoiling member, said detent being pivoted out of engagement with the trigger by recoil movement of the recoiling member thereby permitting the sear to return to its cocked position under the bias of said first resilient means, said second notch arranged to be engaged by the forward end of the head of said detent if the trigger remains pulled after the recoiling member returns to battery position, thereby requiring release of the trigger pull to render the trigger operative.

11. In a magazine firearm, the combination of a trigger frame defining a magazine opening, a magazine latch pivotally mounted in the frame adjacent said magazine opening, a rearward projection on said latch, a pivoted sear, a safety member slidably mounted in the trigger frame under the sear, an upstanding locking member on said safety adapted to engage said sear in one position of said safety, a plurality of notches in the top surface of said safety member and disposed along the line of movement thereof, a vertically movable detent mounted in the trigger frame above said safety member and having a base shaped to engage any one of said notches, said detent arranged to engage one said notch at the sear engaging position of said safety member, and a compressed spring mounted between said detent and said magazine latch projection.

12. In a magazine firearm, the combination of a trigger frame, a pivoted magazine latch, a pivoted sear, a safety member slidably mounted in said trigger frame beneath said sear for movement between two positions respectively of engagement and non-engagement with said sear, a detent member movably mounted in said trigger frame and arranged to engage said safety member in either of its two positions, and a compressed spring mounted between said detent member and said magazine latch, said spring operating to hold said detent member in engagement with said safety member and to impart a pivotal bias to said magazine latch.

13. In a magazine firearm the combination of a trigger frame, a magazine latch pivotally mounted on a transverse pin in the trigger frame, a sear pivotally mounted on said transverse pin, a safety member slidably mounted in said trigger frame beneath said sear for movement between two positions respectively of engagement

and non-engagement with said sear, a detent member movably mounted in said trigger frame and arranged to engage said safety member in either of its two positions, and a compressed spring mounted between said detent member and said magazine latch, said spring operating to hold said detent member in engagement with said safety member and to impart a pivotal bias to said magazine latch.

14. In an automatic firearm in combination, 10 a recoiling member reciprocable in a straight line path, a trigger frame, a sear pivotally mounted on the trigger frame and arranged to engage said recoiling member near the forward end of its movement, a trigger pivotally secured to said 15 sear, resilient means mounted between said trigger and said sear and operating to bias said sear

into a cocked position relative to said recoiling member, stop means on said trigger frame for limiting the pivotal movement of said trigger under the bias of said first resilient means, means 5 engaging said trigger to provide a fulcrum about which said trigger may be pulled thereby pivoting said sear out of its cocked position, said last mentioned means including a projection extending into the recoil path of said recoiling member and actuated thereby to remove said last mentioned means from engagement with said trigger, thereby permitting said sear to return to its cocked position under the bias of said resilient means to engage said recoiling member in its forward movement.

JOHN C. GARAND.
